UNITED STATES PATENT OFFICE.

ELLA SUE HAWKINS, OF ACTON, NORTH CAROLINA.

CROCHETING-NEEDLE.

1,208,958.

Specification of Letters Patent. Patented Dec. 19, 1916.

Application filed June 20, 1916. Serial No. 104,685.

To all whom it may concern:

Be it known that I, ELLA SUE HAWKINS, a citizen of the United States, residing at Acton, in the county of Buncombe and State 5 of North Carolina, have invented certain new and useful Improvements in Crocheting-Needles, of which the following is a specification.

This invention relates to needles, and has 10 particular reference to improvements in crocheting or other needles having a needle portion proper and a handle portion, the principal object of the invention being to so construct these portions as to render them 15 separable so that the handle may be utilized as an inclosing means for the needle proper when the same is not in use to prevent the hook upon the end of the needle portion proper from catching in other articles carried 20 in a basket or bag in which the needle has been placed, and to also obviate the liability of breakage or mutilation of the hook, due to its contact with other articles.

The invention contemplates the provision 25 of a hollow handle having an open end to receive a portion of the needle proper to support the same in an operative position, the handle being adapted to receive the needle proper when the article is not in use, 30 and it is another object of the invention to so construct the two sections of the needle that the flattened finger engaging portion as commonly provided upon the needle proper, will act as a stop means to limit the movement 35 of the needle proper within the handle when the article is in either an operative or inoperative position.

A further object of the invention is to provide a needle of this character which 40 will have the two parts thereof so constructed as to permit of the operation of the needle proper from an operative to an inoperative position or vice versa with respect to the handle in a minimum of times and with but 45 slight exertion, and to provide a construction of this character which will be practical, as well as thoroughly reliable and efficient.

With the foregoing and other objects in 50 view, the invention consists in the novel features of construction, combination and arrangement of parts, as will be hereinafter more fully described, illustrated in the accompanying drawings, and claimed.

55 In the drawings: Figure 1 is a view in side elevation of the preferred embodiment

of the invention with parts broken away. Fig. 2 is a sectional view showing the needle proper arranged in an inoperative position within the handle. Fig. 3 is a view, partly 60 in section and partly in elevation of the separated parts of a slightly modified form of the invention. Fig. 4 is a view similar to Fig. 3 of another slight modification, the two parts of the article in this instance, 65 however, being shown in engaged relation. Fig. 5 is a transverse section in the line 5—5 of Fig. 4. Fig. 6 is a view similar to Fig. 5 of a further modification; and Fig. 7 is a view similar to Fig. 3 of still another modification. 70

Referring to the drawings by numerals, and more particularly to Figs. 1 and 2, wherein is illustrated the preferred embodiment of the invention, 1 designates the 75 needle portion proper and 2 the handle thereof. The portion 1 is of the ordinary construction, that is, it includes a shank 3 terminating in a hook 4 and an intermediate flattened finger engaging portion 5. 80 The shank 3 is screw threaded for a portion of its length adjacent one end of the flattened portion 5, as indicated at 6, a shoulder 7 being thus provided between the shank and flattened portion adjacent its 85 edges, for a purpose which will presently appear. The opposite end of the flattened portion terminates in a threaded stud 8 which is of a size in cross section corresponding to the size of the threaded portion of the shank 3, and in a manner similar to the first mentioned shoulder, a second shoulder 9 is provided between this stud and the flattened portion, for a purpose which will likewise presently appear. 90

The handle 2 is of a tubular construction and is preferably closed at one end and open at the other, the internal diameter thereof corresponding to the diameter of the shank 3 and stud 8 of the needle portion proper, 100 or at least such diameter being equal to that of the shank and stud, adjacent the open end of the handle, and as illustrated this handle is internally threaded adjacent its open end as indicated at 10, the diameter of the tube being sufficiently great to allow the shank 3 to be arranged therein. 105

From the foregoing description taken in connection with the accompanying drawings, the method of operation of the improved needle will be apparent. When it is desired to adjust the shank or needle proper 110

to an operative position with respect to the handle, from the position shown in Fig. 2 the shank is merely unscrewed from engagement with the threads 10 and then withdrawn 5 from the handle and reversed so that the stud 8 may be threaded into the handle and of course in adjusting the shank to an inoperative position within the handle the stud 8 is unscrewed and the shank arranged within the handle and the threads of the stud 8 engaged with the threads 10, the shoulders 7 and 9 in either instance serving to limit such threading operation, as will be understood, so that while the shank will be retained 10 securely engaged with the handle, no binding action of the threads 6 and 8 with the threads 10 will take place, as would be the case were the shoulders not provided thereby permitting of the ready actuation 15 of the sections 1 and 2 from an operative to an inoperative position or vice versa. Thus it will be seen that when the shank is arranged within the handle and the needle placed within a work basket or the like the hook 4 will be prevented from catching in or becoming tangled with other articles in the basket.

In Fig. 3 of the drawings a slight modification of the invention has been illustrated 30 which consists in providing the handle 2, adjacent its open end, with an annular depression 11 to be engaged by either of the annular enlargements 12 or 13 upon the shank 3 or stud 8, respectively, the operation 35 of this embodiment of the invention consisting in merely snapping the parts in engagement. It is to be noted that the shoulders between the flattened portion and the shank and stud in this instance are also adapted 40 for engagement with the end of the handle to limit the movement of the needle portion proper therein.

Figs. 4 and 5 illustrate another slight modification which is somewhat similar to the showing in the modification just mentioned, in that depressions 14 are provided 45 in the handle to receive the enlargements 15 and 16 on the shank and stud respectively of the needle portion proper. In this embodiment, however, the depressions and enlargements do not extend throughout the circumference of the handle, shank and stud, but extend only partially therearound so that

rotation of the needle portion relative to the handle is prevented.

In Fig. 6 the stud has been shown as split 55 to provide spring tongues 17 which are adapted for frictional engagement with the handle, the shank being split likewise as at 18 for a similar purpose.

As illustrated in Fig. 7 the handle has a bayonet slot 19 formed therein to be engaged by either of the pins 20 or 21 upon the shank or stud respectively of the needle portion.

It is to be noted that the same general 65 method of operation is prevalent in each of the forms of the invention, and also that in every instance the shoulders between the shank and flattened portion and the stud and flattened portion coöperate with the securing 70 means between the handle and the needle portion to limit movement of the needle portion within the handle, for the purposes previously mentioned.

From the foregoing description taken in 75 connection with the accompanying drawings, it is thought that the construction and operation of the improved needle will be clearly understood, and while I have herein shown and described certain specific embodiments 80 of my invention, I do not wish to be limited therein, except for such limitations as claims may import.

What is claimed is:—

1. A needle including a shank having a 85 flattened portion formed intermediately thereof, a tubular handle to receive either end of the shank adjacent opposite ends of the flattened portion, the flattened portion being adapted to abut the handle to limit 90 movement of the shank therein, for the purpose set forth.

2. A needle including a shank having a flattened portion formed intermediately thereof, a tubular handle to receive either 95 end of the shank, the said shank, adjacent either end of the flattened portion, being provided with means for positive and detachable engagement with the handle, for the purpose set forth.

In testimony whereof I affix my signature in the presence of two witnesses.

ELLA SUE HAWKINS.

Witnesses:

J. B. CAIN,
E. S. RICKMAN.
